UNITED STATES PATENT OFFICE

2,194,630

APPARATUS FOR THE PRODUCTION OF GAS

Charles W. Andrews, Chicago, Ill., assignor to
H. A. Brassert & Company, Chicago, Ill., a cor-
poration of Illinois

Application June 18, 1937, Serial No. 148,905

7 Claims. (Cl. 126—182)

This invention relates to a new and improved apparatus for the production of gas and more particularly to a mechanically operated producer or water gas generator.

5 This invention is in the nature of a modification or improvement of the apparatus disclosed in Patent No. 1,709,335 issued April 16, 1929, jointly to me and William B. Chapman.

This form of apparatus comprises a grate 10 above a windbox with a rotating beam moving directly above the grate. The beam in the prior patent extends across the grate and, when rotated, not only agitates the firebed but also urges a portion of the ash through the grate while urging the major portion of the ash outwardly over the edge of the grate. The ash falling over the edge of the grate is gradually removed by mechanical means during the operation.

It has been found in operation of the former 20 form of apparatus that the smaller proportion of ashes passing through the grate into the windbox are quite thoroughly burned and do not ordinarily contain more than ten percent of combustible matter. On the other hand, the 25 material discharged over the peripheral edge of the grate has been found to average in some cases as high as forty percent carbon.

It is an object of the present invention to provide a gas making apparatus which gasifies the fuel with a minimum loss of combustible material.

30 It is a further object to provide a construction in which the major portion of the ash is passed through the grate.

35 It is also an object to provide an apparatus with an agitating beam which is largely instroking in effect so as to minimize the discharge of ash over the edge of the grate.

40 It is an additional object to provide a construction in which the ash is retained upon the grate for thorough combustion and agitation to reduce the ash to such sizes as will pass through the grate.

45 It is a further object to provide an apparatus which is adapted for commercial production and use.

Other and further objects will appear as the description proceeds.

50 I have shown a preferred embodiment of my invention in the accompanying drawings, in which—

Figure 1 is a vertical transverse section of the lower portion of the gas making apparatus;

55 Figure 2 is a plan view of the construction of Figure 1; and

Figures 3 and 4 are fragmentary sections taken on lines 3—3 and 4—4 of Figure 2.

In the drawings, the fuel chamber 11 is defined by the walls 12, and its bottom is largely closed by the circular grate 13. This grate 13, 5 as shown in Figure 2, is made up of a plurality of sections which are provided with openings permitting the passage of material downwardly through the grate when that material has been reduced to a predetermined size. The bottom of 10 the gas making apparatus is closed by the conical hopper 14, with a removable lower closure 15 through which ashes may be withdrawn. The air admission passage 16 enters into the side of 15 the hopper 14, its upper end being protected by 15 the deflecting means 17 so that ashes do not fall down into the passage. A perforated pipe 18 is provided for wetting the ashes, as desired.

The water connection 19 extends downwardly 20 through the central opening 20 in the grate and is connected to the agitating beam 21. This beam, as shown in Figures 1, 3 and 4, is hollow and is water cooled by water introduced through pipes 22 and withdrawn through pipe 23. The outer ends of the beam 21 are connected at 24 25 and 25 to a rotating platform 26 which serves to receive material passing outwardly over the periphery of the grate 13. The platform 26 has connected thereto the gear ring 37 which is driven by pinion 28 carried on shaft 29. This 30 shaft 29 is driven by means of gear 30 through the worm gear 31 on shaft 32, which is rotated by any suitable source of power. The adjustable scraper 33 is provided as shown in Figure 2, this scraper intercepting material on the platform 26 as that platform rotates, and forcing the 35 material outwardly into the discharge passage 34.

As shown in Figures 3 and 4, the upper face 40 of the rotating beam 21 inclines upwardly away from the leading edge portions 35 and 36. The rear walls 37 and 38 of the beam are substantially vertical. As clearly shown in Figure 2, the major portion of the leading edge of each half of the beam is concave, while the outer portions 39 and 40 of the leading edges adjacent the periphery of the grate are convex and sloped rearwardly relative to the direction of rotation of the beam.

In the operation of the generator it will be understood that a bed of fuel will be placed in 50 the chamber 11 and ignited in the usual manner. It will be understood that the apparatus may be used for the production of producer gas by introducing steam and air continuously through the passage 16 or to produce water gas by in- 55

roducing steam and air alternately. The apparatus may be used to carry on any usual or customary cycle of operations in the making of gas by known methods using up or down runs or combinations thereof. The beam 24 is rotated during the process jointly with the platform 26. This beam serves to force material ahead of it and to urge the smaller material through the openings in the grate. The mass of material is gradually lifted over the inclined faces of the beam and then dropped suddenly past the vertical rear edge of the beam, which aids in breaking up the clinkers which may form and reducing the material to the desired size. The concave leading edges 35 and 36 tend to maintain the material on the grate rather than to urge it off of the edge of the grate onto the platform 26.

Should the apparatus tend to clog by the packing of material in front of the beam, which material is carried around with the beam, this material will advance in front of the concave section and tend to fill up the concavity. This material will then serve in general the same effect as the front edge of the beam and by filling up the concavity will temporarily cause an outstroking action to relieve the packing or clogging. The outer portions 39 and 40 of the leading edge are outstroking so as to assist in the discharge onto the platform 26 of material which reaches the periphery of the grate. It will be apparent that the instroking beam will tend to grind any clinker which forms to ashes and to maintain material centrally of the chamber and over the grate until the combustible material has been largely burned to ash.

It will be understood, also, that the speed of rotation of the beam may be varied to suit the working conditions and operating cycle, and also the character of the fuel being used. The outstroking outer end portions of the beam will aid in forcing any large pieces of clinker which may form, against the side walls and thus break them up and force the broken pieces out of the chamber. The beam formed as shown will be instroking over the working zone of the grate and outstroking over the center of the grate and at the ends. For proper operation the combustion zone is maintained above the rotating beam and the clinker is solid and brittle when it reaches the beam agitation zone so that it is readily broken up by the beam action.

This new form of beam and method of operation results in considerably reducing the combustibles lost over the periphery of the grate by the use of former types of apparatus and methods.

While I have shown and described a preferred embodiment of my invention it is capable of change and modification to meet varying conditions and requirements and I contemplate such changes as come within the spirit and scope of the appended claims.

I claim:

1. In a gas making apparatus, a fuel chamber, a grate at the bottom of the chamber, means adjacent the periphery of the grate for receiving ash discharged therefrom, an agitating beam located above and adjacent the grate, means for

rotating said beam, the leading edge of said beam being generally concave in plan view.

2. In a gas making apparatus, a fuel chamber, a grate at the bottom of the chamber, means adjacent the periphery of the grate for receiving ash discharged therefrom, an agitating beam located above and adjacent the grate, means for rotating said beam, the leading edge of said beam being generally concave in plan view and the upper surface of the beam inclining upwardly away from the leading edge of the beam.

3. In a gas making apparatus, a fuel chamber, a grate at the bottom of the chamber, means adjacent the periphery of the grate for receiving ash discharged therefrom, an agitating beam located above and adjacent the grate, means for rotating said beam, the leading edge of said beam being generally concave in plan view, the upper surface of the beam inclining upwardly away from the leading edge of the beam, and the rear edge of the beam being substantially vertical.

4. In a gas making apparatus, a fuel chamber, a grate at the bottom of the chamber, means adjacent the periphery of the grate for receiving ash discharged therefrom, an agitating beam located above and adjacent the grate, means for rotating said beam, the leading edge of the major portion of the beam being concave in plan view and tending to maintain material on the grate while agitating said material, the end portions of the beam being convex and outstroking to discharge material upon the ash receiving means, the upper surface of the beam inclining upwardly away from the leading edge of the beam, and the rear edge of the beam being substantially vertical.

5. In a gas making apparatus, a fuel chamber, a circular grate at the bottom of the chamber, agitation and discharge means associated with the grate comprising a beam extending across the grate and a discharge platform around the periphery of the grate, means for rotating the beam and platform and means for removing material from the platform, the leading edge of the major portion of the beam being concave in plan view and tending to maintain material on the grate while agitating said material.

6. In a gas making apparatus, a fuel chamber, a circular grate at the bottom of the chamber, agitation and discharge means associated with the grate comprising a beam extending across the grate and a discharge platform around the periphery of the grate, means for rotating the beam and platform, and means for removing material from the platform, the leading edge of the major portion of the beam being concave in plan view and tending to maintain material on the grate while agitating said material, the end portions of the beam being convex and serving to discharge material onto the platform.

7. A method of ash disposal in a gas generator, in which the loss of combustibles is thereby reduced, which comprises solidifying liquid ash to clinker immediately above the base of the generator and maintaining the clinker and ashes over the grate openings while, by a combined rotary instroking and vertical agitation action, the clinker is largely reduced to a size which will pass through grate openings.

CHARLES W. ANDREWS.
